This is a continuation-in-part of my application for a patent, Serial No. 714,199, filed December 5, 1946, and entitled "Surprise Package," which application is now pending.

UNITED STATES PATENT OFFICE

2,447,946

RATTLER

James L. La Forge, Caruthersville, Mo.

Application December 5, 1946, Serial No. 714,199

3 Claims. (Cl. 46—118)

1

This invention relates to surprise packages and more particularly to a device having a rattler which is inoperative when disposed under tension in the package but which becomes operative upon the opening of the package to produce a rattling sound, said device further having a figured member also under tension which, upon the opening of said package, is projected out of the open package, said rattler and said figured member causing surprise or consternation to the person opening the package.

The invention resides in the novel details of construction and combinations of parts as will be disclosed more fully hereinafter and particularly covered by the claims.

Referring to the accompanying drawings forming a part of this specification and in which like numerals designate like parts in all the views,

Fig. 1 is an elevational view of a device made in accordance with this invention; and

Fig. 2 is a transverse sectional view of the device taken as on the line 2—2 of Fig. 1 and looking in the direction of the arrows.

The device comprises a plate 2 of relatively stiff material which is preferably rectangular and adapted to closely fit an envelope generally identified by the dashed lines 3, said plate provided with an opening 4 more or less centrally thereof. To this plate a flat figured member 5 is loosely and pivotally secured as by the rivet 6, said member having a depending hook 7 relatively closely adjacent said rivet at one end of the member, the opposite end of said member being fashioned and ornamented as for example to represent the head end of a snake.

A motor in the nature of a rubber band 10 is passed through a hole 11 in said plate, and stretched across the opening 4 with its ends engaged by the hook 7 of the figured member, said rubber band being of a length normally to place said hook under slight tension so as to impart a turning movement of said member about said rivet. A rattle in the nature of a spinner 12 is inserted between the bights or strands of said rubber band at approximately its middle, and given several twists so as to increase the tension of the rubber band as will be readily understood from the drawings, the dimensions of the plate opening 4 being greater than the dimensions of said spinner. Preferably the figured member has a portion such as 13 which overlies the twisted spinner when said member is moved to the position shown in full lines in Fig. 1, thereby tending to hold the spinner in its twisted condition.

When the device is disposed in an envelope 3 and the rubber band 10 is tensioned, the member 5 is held in a position as shown in Fig. 1, the hook 7 being held in the tensioned position by the tension of the rubber band 10. The envelope 3 is then closed and the flap 14 turned over its usual fold line indicated at 15, thereby retaining the figured member 5 and spinner 12 under tension in the position shown in full lines. When the flap 14 is reversely turned, or the envelope 3 is opened along said fold line 15, the figured member 5 will be freed and will spring out of the envelope due to the tension of the rubber band 10 on its hook 7, this movement being relatively rapid and causing surprise to the person opening the envelope. Coincidental with this movement of the figured member 5, is the release of the spinner 12 which, due to the spring action and twist of the rubber band 10, will rapidly rotate and strike the inner surfaces of the envelope to produce a rattling sound, which adds to the surprise or consternation of said person.

- 2 At the pivot end of the figured member there is provided a straight edge portion 20 which is so positioned as to contact the closed or folded end 21 of the envelope when said member springs upwardly, said edge thereby constituting a stop for the movement of said member when the head end thereof reaches substantially the dotted line position shown in Fig. 1.
- 3 It is obvious that those skilled in the art may vary the details of construction and arrangements of parts without departing from the spirit of this invention, wherefore it is desired not to be limited to the exact foregoing disclosure except as may be required by the claims.

What is claimed is:

- 4 1. A rattler comprising a plate having an opening, a figured member pivotally mounted at one end on said plate in parallelism therewith, an elastic band motor comprising two parallel strands extending across said opening said strands attached at one end to said plate and attached at the other end to said member adjacent its pivotal mounting, a sound producing element positioned between said strands within said opening, said element when manually rotated twisting said strands together and placing said member under operative tension, said plate adapted to be positioned in an envelope with said member depressed against said operative tension and retained in such depressed position by the folded flap of the envelope until said member is suddenly projected in a pivotal manner out of the envelope by virtue of the tension of said motor when the envelope is opened along the line of its folded flap, whereupon said element is rapidly rotated to create a sound against the inner surfaces of the envelope by the

untwisting of said strands, when the envelope is opened along the line of its folded flap.

2. A rattler comprising a plate having an opening, a figured member pivotally mounted at one end on said plate in parallelism therewith, an elastic band motor comprising two parallel strands extending across said opening said strands attached at one end to said plate and attached at the other end to said member adjacent its pivotal mounting, a sound producing element positioned between said strands within said opening, said element when manually rotated twisting said strands together and placing said member under operative tension, said plate adapted to be positioned in an envelope with said member pivotally depressed against said operative tension and retained in such depressed position by the folded flap of the envelope, said member overlying a portion of the manually rotated element when said member is in such depressed position and until said member is suddenly projected in a pivotal manner out of the envelope by virtue of the tension of said motor when the envelope is opened along the line of its folded flap, whereupon said element is rapidly rotated to create a sound against the inner surfaces of the envelope by the untwisting of said strands, when the envelope is opened along the line of its folded flap.

3. A rattler comprising a plate having an open-

ing, a figured member pivotally mounted at one end on said plate in parallelism therewith, said member having stop means adapted to limit its pivotal movement in one direction, an elastic band motor comprising two parallel strands extending across said opening said strands attached at one end to said plate and attached at the other end to said member adjacent its pivotal mounting, a sound producing element positioned between said strands within said opening, said element when manually rotated twisting said strands together and placing said member under operative tension, said plate adapted to be positioned in an envelope with said member depressed against said operative tension and retained in such depressed position by the folded flap of the envelope until said member is suddenly projected in a pivotal manner out of the envelope by virtue of the tension of said motor when the envelope is opened along the line of its folded flap, whereupon said element is rapidly rotated to create a sound against the inner surfaces of the envelope by the untwisting of said strands, when the envelope is opened along the line of its folded flap, the stop means of said member adapted to engage a folded end of the envelope when said member is fully projected therefrom.
